UNITED STATES PATENT OFFICE.

LUCIUS W. POND, OF WORCESTER, MASSACHUSETTS.

METAL-PLANING MACHINE.

SPECIFICATION forming part of Letters Patent No. 417,084, dated December 10, 1889.

Application filed March 23, 1889. Serial No. 304,438. (No model.)

To all whom it may concern:

Be it known that I, LUCIUS W. POND, a citizen of the United States, and a resident of Worcester, in the county of Worcester and State of Massachusetts, have invented a new and useful Improvement in Metal-Planing Machines, of which the following is a specification, reference being had to the accompanying drawings, representing such portions of a metal-planing machine as are necessary to illustrate the nature of my invention and the method of embodying the same, and in which—

Figure 1 represents a side elevation of a portion of a metal-planing machine. Fig. 2 is a top view of the bed and reciprocating table, a portion of the latter having been broken away in order to disclose the belt-shipping mechanism. Fig. 3 shows one of the shipping-dogs attached to the table in the beginning of its contact with the vibrating shipping-levers. Fig. 4 represents the same dog during its period of contact with the vibrating shipping-levers. Fig. 5 represents the dog at the close of its period of contact with the vibrating shipping-levers. Fig. 6 shows one of the vibrating shipping-levers detached. Fig. 7 represents the hinged dog in perspective view. Fig. 8 represents a portion of the rigid jaw, and Fig. 9 represents the adjustable toe attached to the portion of the rigid dog represented in Fig. 8, but shown detached therefrom.

Similar letters refer to similar parts in the different views.

My present invention relates to the shipping mechanism of a metal-planing machine; and it consists in providing means whereby the shipping mechanism may be operated either with a quicker or a slower motion relatively to the speed of the reciprocating table, to provide means for disconnecting the table and the shipping mechanism upon the reverse motion of the table, and in case separate and independent shipping mechanisms are employed for shipping the driving-belts to so connect the separate shipping mechanisms that they may both be operated by hand.

In the accompanying drawings, A denotes the bed; B, the reciprocating table; C D, the driving-pulleys; E F, loose pulleys; G G', belt-eyes attached to the sliding rods G² G³.

H is a hollow spindle journaled in a bearing in the bed of the machine, having attached to its outer end the lever H' and to its inner end the radial arm H², connected by means of the links H³ and H⁴ and the bell-crank lever H⁵ with the sliding rod G². 55

J is a spindle journaled in the hollow spindle H, and having the lever J' attached to its outer end and the radial arm J² attached to its inner end and connected by means of the links J³ and J⁴ and the bell-crank lever J⁵ with the sliding rod G³. 60

To the edge of the reciprocating table B, I attach the plate K, adjustably attached to the table by means of a bolt a, whose head is held in a T-shaped slot b in the edge of the table. A dog K' is hinged to the plate K by the pin K², having a finger K³ in position to engage 70 the lever H', and a lateral projection or spur K⁴ in position to engage the lever J'. 05

To the edge of the table B, I attach a dog L, similarly adjustable along the edge of the table and having a finger L' in position to engage the lever J', and a toe L² in position to engage both of the levers H' J' as the table is moved in the direction of the arrows in Figs. 3 and 4. The toe L² has teeth L³, engaging similar teeth L⁴ upon the dog L, and a shallow 80 channel or groove L⁵ to receive the spur L⁶ on the dog L, and the toe L² is adjustably attached to the dog L by means of a bolt L⁷, screwing into the toe L² and passing through the slot L⁸ in the dog. 85

The lever H' has a slot N, and the lever J' carries a pin N', which enters the slot N, so that after a slight movement of the lever J', by means of the hand-lever N², projecting from the hub of the lever, the lever H' will be 90 moved by means of the pin N', causing both of the shipping mechanisms to be operated by means of the hand-lever N².

As the work is being fed to the cutting-tool the table is moved in the direction of the arrow shown in Fig. 3, and as the dog L is brought toward the vibrating levers H' J' the finger L' is first brought into contact with the lever J', operating the sliding rod G³ and moving the belt from the driving-pulley C to the loose pulley E, and moving the lever J' in advance of the lever H', as shown in Fig. 4. At this point the toe L² is brought against the lever H', operating the sliding rod G² through 100

the connecting mechanism to carry the belt from the loose pulley E to the tight driving-pulley D and reversing the motion of the table, which is caused to move in the direction of the arrows in Figs. 1 and 2. As the hinged dog K' is brought toward the levers H' J', the finger K³ is made to strike against the lever H', and through the connected mechanism moving the driving-belt from the driving-pulley D to the loose pulley F, the farther advance of the table B serves to bring the laterally-projecting spur K⁴ against the lever J', causing the belt to be carried from the loose pulley E onto the driving-pulley C, and a feeding motion given to the table in the direction of the arrows in Figs. 3 and 4 until the dog L is again brought into action and the motion of the table again reversed. As the table is reversed in the direction of the arrow shown in Fig. 1, it is sometimes desirable to continue the motion of the table beyond the point at which the levers H' J' are acted upon by the dog K', in order to withdraw the work from the cutting-tool in convenient position for adjustment, inspection, or other purposes. This is readily accomplished by lifting the hinged dog K' in the position indicated by broken lines at K⁵, Fig. 1, allowing the dog to pass over the top of the levers H' J'. The toe L² is vertically adjustable by means of the bolt L⁷ and slot L⁸, so that it may be made to strike against the levers H' J' at different distances from the center of the spindle J, causing the angular velocity of the levers to be varied relatively to the speed of the reciprocating table B.

In the accompanying drawings I have shown the vertically-adjustable toe L² and the hinged dog K' in connection with separate and independent shifting mechanisms; but they can be used equally well with a single shifting mechanism, by which both belts are simultaneously shifted, or with any of the devices for shifting the belts of a metal-planing machine in which a vibrating lever is employed like or similar to the levers H' or J'.

What I claim as my invention, and desire to secure by Letters Patent, is—

1. In a metal-planing machine, the combination, with a movable belt-eye and a vibrating lever attached to a spindle journaled in the bed of the machine and having operative mechanism by which it is connected with said movable belt-eye, of an actuating-dog ad-

justably attached to the reciprocating table, 55 said dog being hinged so that it may be removed from the path of said vibrating lever, substantially as described.

2. In a metal-planing machine, the combination, with a movable belt-eye and operating mechanism comprising a vibrating lever journaled in the bed of the machine, of a plate K, adjustably attached to the edge of the reciprocating table, and a hinged dog K', hinged to said plate and so arranged that in the normal position of said dog it is caused to strike against said vibrating lever, substantially as described.

3. In a metal-planing machine, the combination, with a belt-shifting mechanism comprising a vibrating lever journaled in the bed of the machine, of a dog attached to the edge of the reciprocating table and having a vertically-adjustable toe attached thereto, whereby the angular velocity of said vibrating arm is varied relatively to the speed of the reciprocating table by causing said adjustable toe to strike said vibrating lever at varying radial distances, substantially as described.

4. In a metal-planing machine, the combination, with a belt-shifting mechanism comprising a vibrating lever, substantially as described, of an actuating-dog attached to the reciprocating table of the machine, said dog being vertically adjustable, so as to be made to strike said vibrating lever at different radial distances from its axis of vibration for the purpose of varying the angular velocity of said lever relatively to the speed of the reciprocating table, substantially as described.

5. In a metal-planing machine, the combination, with the vibrating levers H' J', having a common axis of rotation and having connected belt-shifting mechanisms, of an actuating-dog attached to the table of the machine and arranged to strike said levers at different distances from their axis of rotation, substantially as described.

6. The combination of the plate L, finger L', adjustable toe L², and belt-shifting mechanism comprising the levers H' J', connected with movable belt-eyes, substantially as described.

LUCIUS W. POND.
